UNITED STATES PATENT OFFICE.

MIKE PEABODY, OF NEW YORK, N. Y.

DESIGN FOR A CLOSET-SHIELD.

SPECIFICATION forming part of Design No. 23,561, dated August 14, 1894.

Application filed July 19, 1894. Serial No. 518,055. Term of patent 14 years.

To all whom it may concern:

Be it known that I, MIKE PEABODY, a citizen of the United States, residing in the city, county, and State of New York, have invented and produced a new and original Design for Closet-Shields, of which the following is a specification.

In the drawings Figure 1, is a perspective elevation of the shield; Fig. 2 a sectional elevation approximately on the line x, x , Fig. 1; Fig. 3 a front elevation, and Fig. 4 a rear elevation.

The essential feature of the design is its configuration, which is generally that of an ellipse in plan, divided transversely to its axis, and comprises the pendent and semi-ellipti-

cal web a , having a likewise conformed angular projection b , provided with apertures c . The elevation of the web a shows it to be crescent shaped, and at its lower edge merges into the projection b at the extreme end of both, as seen most clearly in Figs. 2 and 3.

Having described my design, I claim—

The design for a closet shield, substantially as herein shown and described. 25

Signed at New York, in the county of New York, State of New York, this 18th day of July, 1894.

MIKE PEABODY.
